UNITED STATES PATENT OFFICE.

FRANK CLIFFORD, OF MILWAUKEE, WISCONSIN.

TOY.

1,254,384.

Specification of Letters Patent. Patented Jan. 22, 1918.

Application filed April 12, 1917. Serial No. 161,646.

To all whom it may concern:

Be it known that I, FRANK CLIFFORD, a citizen of the United States, residing at Milwaukee, in the county of Milwaukee and State of Wisconsin, have invented certain new and useful Improvements in Toys, of which the following is a specification.

This invention relates to toys and especially to chromatic toys of that class which are held in the hand and caused to revolve, and the revolving part provided with a plurality of sheets or disks of different colors loosely mounted upon a pin and contacting with the revolving member, and by reason of such contact, are caused to rotate at varying speeds and so display a variety of colors, which, through the change in position of said sheets, will be of infinite variety as to design and combination of colors.

Another object of the invention is to provide in a revolving chromatic toy a circular rotatable member weighted on one side of its center by means of which weight said member may be caused to rotate rapidly about a central journal when the latter, held in the hand, is given slight rotary movement, the rotating member through frictional contact with a number of sheets of different colors placed eccentrically upon the pivot will be caused to turn therewith at different speeds, and moving one upon the other disclose an infinite change in colors and designs during the entire time of rotation of said parts.

A further object of the invention is to provide a chromatic toy of simple construction which may be made very cheaply and which may be readily operated by children to produce, through rotation thereof, and of colored disks mounted thereon figures of infinite variety both as to design and color, and through such changes give pleasure to the child and teach him the values of various colors.

With the above and other objects in view, the invention consists in the novel construction, combination, and arrangement of parts hereinafter described, pointed out in the appended claims and illustrated in the accompanying drawings, in which—

Figure 1 is a side elevation of the improved toy looking at the edge of the revolving member and the colored sheets mounted thereon.

Fig. 2 is a side view of the revolving mem-

ber and several colored sheets that rotate in connection with said member,

Fig. 3 is a view of the rotating member as seen from the opposite side,

Fig. 4 is a cross sectional view of a modified form of the invention, and

Fig. 5 is a face view of one of the colored sheets.

In the drawings, 10 indicates a handle which, in the present instance, is shown as made of wire bent upon itself and twisted together, one end being extended to form a pin 11, upon which a rotating member 12 is mounted.

The rotating member is circular in shape, 70 and has a hub 13 that turns freely on the pin 11 of the handle, said member being made of any suitable material and may be in the form of a wire ring 14 connected by a pair of wire spokes 15 to the hub 13 which 75 may also be made of wire, or made of a disk of sheet metal, paper, celluloid, or other convenient and suitable material. Whether made in the form of a disk or of a ring as shown, there will be at one side of the 80 periphery of said member a weight 16 sufficiently heavy to cause a member to rotate when the handle, grasped by a person, is given a slight rotating motion about an axis parallel with the pin 11. The weight 16 85 through centrifugal force, will rotate the member 12 rapidly about the pin 11. To hold the member upon the pin there is mounted at its inner end a small disk 17 which limits the inward movement of the 90 rotating member, and to maintain the same on the pin, a small block of rubber 18 having an opening therethrough is slipped over the outer end of the pin and against the hub 13 of the member 12. To reduce friction between the block and the hub, the block is incased as shown in the drawing in a strip of sheet metal 19.

To produce the chromatic effects, a number of sheets 20 which may be paper, celluloid, or other material sufficiently stiff for the purpose, are cut into circular, elliptical or other form, as in Fig. 5, and each provided with an eccentric opening 21 much larger than the pin 11 and adapted to turn 100 more or less freely thereon. These sheets may also have an arcuate opening 22 on the opposite side of the center thereof for the purpose of assisting in the variations of color and design when the toy is in use. 110

To operate the toy, the various sheets 20, each of which, as above stated, is of a different color, are placed upon the pin 11, the latter passing through the openings 21 or 22, as in Fig. 2 where the pin is shown passing through the opening 21 in the outermost sheet and through the arcuate opening 22 in the sheet below. Against the outermost sheet is slipped a backing sheet 23 preferably of a neutral color and of circular shape, against which sheet is placed the rotating member 12 followed by the retaining block 18 which bears against the hub 13 and holds the sheets 20 against the disk 17 with more or less pressure as may be desired. The handle 10 is now given the twirling motion described to cause the rotating member to turn rapidly about the pin 11, which movement through the frictional contact of the sheets with the backing 23 and the latter with the rotating member, will cause said sheets to turn with the rotating member at greater or lesser speed depending upon the degree of friction with which said sheets engage each other, the backing sheet and the disk 17, some of the sheets twirling very rapidly while others move at much slower speed, the result being that through the varying positions of the several sheets with relation to each other, one or the other of the several sheets will be caused to be exposed with great prominence and its color will predominate in the form of a circular ring to disappear in a moment and some other color or combination of colors appear, these changes following as long as the member continues to rotate.

As a modification, a straight handle 10^a, Fig. 4, may be substituted for the handle 10 of the first form and instead of or in connection with the disk 11 a rubber block 24 may be mounted on the outer end of the handle to receive the hub of the rotating member 12. Upon this rotating member will be placed the backing sheet 23, and upon this sheet the several colored sheets 20 upon the outermost of which is a small disk of isinglass, celluloid, or like transparent material 25 held in place by the rubber retaining block 18. As thus arranged the chromatic effect will be visible, not to the operator as in Fig. 1, but to some one in front of the toy.

A further modification may be produced by mounting a set of colored sheets upon the hub 13 of the rotating member on the side opposite that shown in Fig. 1, and thus changeable effects of the toy will be visible

not only to the operator but to persons on the opposite side or in front of the toy. 60

A toy constructed as described will be simple, can be made at slight expense and will be of great pleasure not only to children but others more advanced in life who are interested in the changing of colors and their 65 combinations.

What I claim is:

1. A chromatic toy comprising a member weighted at one side of its periphery, an axial pin on a handle carrying said member 70 and adapted to cause its rotation by rapidly moving said parts circularly about an axis parallel to the axis of the rotating member, and colored sheets frictionally contacting with said member.

2. A chromatic toy comprising a handle with a pin shaft, a member rotatable freely upon said pin and weighted at one side of its periphery and adapted to be rotated by the rotating motion of said handle, and a 80 plurality of colored sheets held in frictional contact with said rotating member and each other.

3. A chromatic toy comprising a handle having a bearing pin at one end, a circular 85 member rotatable on said pin, a weight on one side of its periphery, means for retaining said member upon said bearing pin, and a plurality of sheets of different colors eccentrically mounted upon said bearing pin 90 and having a slight frictional engagement with said rotating member and with each other.

4. A chromatic toy comprising a circular member weighted at one side of its periphery 95 and having a central hub, a handle provided with a bearing pin adapted to extend through said hub and cause the rotation of said member by twirling the same in a circular direction about an axis parallel with 100 the axis of the bearing pin, a disk fixed upon said pin at its inner end, a block for holding said member upon the pin, and a plurality of sheets of different colors having eccentric openings therein and adapted to be supported upon said pin between the rotating member and the disk and having a slight frictional contact with said member and each other. 105

In testimony whereof I affix my signature 110 in presence of two witnesses.

FRANK CLIFFORD.
